UNITED STATES PATENT OFFICE.

DONALD M. FERGUSON, OF DETROIT, MICHIGAN, ASSIGNOR TO GENERAL MOTORS COMPANY, OF DETROIT, MICHIGAN, A CORPORATION OF NEW JERSEY.

AUTOMOBILE.

1,232,781.

Specification of Letters Patent. Patented July 10, 1917.

Application filed December 15, 1913. Serial No. 806,703.

To all whom it may concern:

Be it known that I, DONALD M. FERGUSON, a citizen of the United States, residing at Detroit, county of Wayne, State of Michigan, have invented a certain new and useful Improvement in Automobiles, and declare the following to be a full, clear, and exact description of the same, such as will enable others skilled in the art to which it pertains to make and use the same, reference being had to the accompanying drawings, which form a part of this specification.

My invention relates to automobiles and an object of my improvements is to provide an improved construction of the running gear adjacent to the rear axle, and especially to provide an improved construction where a chain is the driving means.

I secure this object in the device illustrated in the accompanying drawings in which,

Figure 1, is an elevation partly in section of an apparatus embodying my invention and so much of an automobile as is necessary to illustrate its connection therewith.

Fig. 2, is a plan view of the same.

Fig. 3, is a sectional detail view showing the construction adjacent to the end of the rear axle.

a indicates the frame work of an automobile. *b* is the casing for the rear axle. *c* is the casing for the equalizing gear formed integral with, or rigidly united to, the casing *b*. *d d* are the driving wheels. *e* is a brake drum which is rigidly secured by bolts in the usual way, one to each of the wheels *d*. *f* is a sleeve journaled upon the casing *b* at its end and having a seat or base *p* upon which the spring *g* may be secured by clips in the usual way. Thus the springs *g* are rigidly secured to the sleeves *f f*. *o* (Fig. 3) is a plate forming part of the brake mechanism and rigidly secured to the sleeve *f* so as to sustain the torque of the brakes. *n n* are radius rods secured to the sleeves *f*. The casing *c* is provided with an opening *q* at the back thereof having a cover *h* which latter may be removed and the equalizing gear removed for inspection or repair. *r* is the driving chain. *i* is a boot or casing in-

closing the driving chain and pivoted at *m* (Fig. 1) to the frame *a* through the medium of the counter shaft or otherwise. There is a rectangular opening *j* in the forward end 55 of the casing *c* to admit of the passage of the strands of the chain *r* and the boot *i* is provided with flanges *k k* adapted to be secured to the casing *c* around said opening.

The sleeves *f* are pivoted upon the casing 60 *b* so as to be adapted to have relative angular movement.

By this construction the casing *b c* is rigidly secured to the boot *i* which latter is pivoted to the frame and the casing *b c* is 65 capable of accommodating itself to the vertical movement of the frame and in doing this may move independent of the sleeves *f f* and the springs *g*. The torque of the brakes is taken immediately by the springs 70 *g* and radius rods *n*.

What I claim is:

1. In an automobile, a casing for the equalizing gearing, a chain boot secured to said casing and pivoted at its end remote 75 from said casing to a support on the frame of the automobile, a casing for the rear axle integral with the casing for the equalizing gearing, a sleeve upon the end of said axle casing and angularly movable thereon, and 80 a body-supporting spring secured to said sleeve.

2. In an automobile, a casing for the equalizing gearing, a chain boot secured to said casing and pivoted at its end remote 85 from said casing to a support on the frame of the automobile, a casing for the rear axle integral with the casing for the equalizing gearing, a sleeve upon the end of said axle casing and angularly movable thereon and 90 a body-supporting spring secured to said sleeve, and a brake mechanism, said sleeve being connected to a part of said brake mechanism so as to receive the torque of the 95 brake.

In testimony whereof, I sign this specification in the presence of two witnesses.

DONALD M. FERGUSON.

Witnesses:

AGNES M. HIPKINS,
VIRGINIA C. SPRATT.
